UNITED STATES PATENT OFFICE.

ROBERT MCKAY, OF DETROIT, MICHIGAN.

DESIGN FOR A TOOL-HOLDER.

SPECIFICATION forming part of Design No. 23,658, dated September 25, 1894.

Application filed April 30, 1894. Serial No. 509,591. Term of patent 7 years.

To all whom it may concern:

Be it known that I, ROBERT MCKAY, a citizen of the United States, residing at Detroit, in the county of Wayne and State of Michigan, have invented certain new and useful Improvements in Tool-Holders for Leather-Channeling Tools, of which the following is a specification, reference being had therein to the accompanying drawings, showing a part thereof.

Figure 1 is a side elevation of my newly designed tool holder. Fig. 2 is a top plan view thereof. Fig. 3 is a front end elevation.

The leading feature of the design is the new configuration comprising a yoke shaped body, having at one side a narrow neck terminating in an inclined head.

A is the yoked shaped body, from which at

the forward end at one side of the middle, projects the upwardly curved neck B.

The sides of the neck merge into the sides of the vertically and laterally inclined head C, which has the tapering upward extension D, and the curved front edge, shown in side elevation at E.

The head on its front face is provided with the inclined cut F.

What I claim is—

The design for a tool holder for leather channeling tools herein described and shown.

In testimony whereof I affix my signature in presence of two witnesses.

ROBERT MCKAY.
